Walter D. Morrison
By Gen. H. Strong, att.

UNITED STATES PATENT OFFICE.

WALTER D. MORRISON, OF SAN FRANCISCO, CALIFORNIA.

MACHINE FOR AUTOMATICALLY SEGREGATING, MEASURING, AND DELIVERING MOLTEN GLASS.

No. 810,167.

Specification of Letters Patent.

Patented Jan. 16, 1906.

Application filed February 16, 1904. Serial No. 193,773.

To all whom it may concern:

Be it known that I, WALTER D. MORRISON, a citizen of the United States, residing in the city and county of San Francisco and State of California, have invented new and useful Improvements in Machines for Automatically Segregating, Measuring, and Delivering Molten Glass, of which the following is a specification.

10 My invention relates to improvements in apparatus for manufacturing glass articles, and pertains particularly to means for segregating a predetermined quantity of molten glass from the melting-pot and delivering it in plastic condition to the molds. Its object is to provide a practical and simple machine which will automatically do the work of the skilled workmen known as the "gatherer" and "presser" now employed, the one to 15 "gather" the glass through an aperture in the melting-pot upon a pontil or punty and transfer it to a mold in the press where the other severs, by means of a pair of shears, the estimated quantity required.

20 The invention consists of the parts and the construction and combination of parts hereinafter more fully described, having reference to the accompanying drawings, in which—

25 Figure 1 is a side elevation of my apparatus, partly in section. Fig. 2 is a front view of same, partly in section. Fig. 3 is a plan view of the revoluble table.

30 A represents a melting-pot of any suitable size, shape, or construction, and 2 is a comparatively small chamber communicating with the pot through an aperture controlled by the gate 3. The material in chamber 2 is maintained in the same heated and plastic

35 condition as that in pot A, and discharge to my apparatus and to the molds is from this chamber. This apparatus comprises a horizontal intermittently-revolvable table 4, mounted on shaft 5, driven from any suitable 40 source of power and provided with a series of radially-disposed pockets 6. This table is arranged in suitable relation to chamber 2, whereby the pockets are adapted to register with an opening 7 in the bottom of the chamber at each successive movement of the table.

45 These pockets are presumed to contain each just the desired amount of material for a jar, bottle, or the-like of a particular size. The pockets 6 are preferably open at top and bottom and preferably in the form of a truncated cone with the lower discharge end larger to

expedite delivery of the heavy viscid contents.

Between the under side of chamber 2 and perforated correspondingly with opening 7 is a hollow water-jacketed plate 7', having a lower cutting edge 7", with which the upper surface of table 4 has a snug sliding fit, the two parts coöperating after the manner of a slide-valve to control the flow from orifice 7, 55 since discharge from chamber 2 is intended to take place only when a pocket is in line with orifice 7. As a pocket approaches opening 7 the bottom of the pocket rides upon a hollow spring-pressed segmental closure-plate 8. The latter is inclined downward at the approach end, as shown at 9, and extends from a point beneath discharge-opening 7 to a point immediately above a mold 10 of a press. The length of the closure-plate is approximately equal to the length of one step movement of the table. The plate 8 is supported from a fixed part and is normally pressed upward into the path of a pocket by the springs 11. Water is admitted to the 60 chamber in plate 8 just as it is to plate 7', as it is essential that the metal parts do not become so hot as to cause the glass to adhere to them.

65 The table is given a step-by-step movement by any suitable means. In the present instance I have shown the shaft 5 as having a bevel-gear 12 engaging a mutilated gear 13 on drive-shaft 14, so that with each revolution of the latter the table is moved to bring 70 the pockets successively beneath opening 7 and over mold 10. The interval between each movement is only long enough to allow one pocket to fill while another is discharging.

75 A plunger 15 is reciprocable in line with opening 7 in chamber 2 and coördinately with the intermittent movement of the table to assist the more rapid filling of the pockets, since the molten glass is comparatively sluggish in its flow. As here shown, the opening 7 is designed to hold more than is required to fill a pocket. The plunger has a movement from a point above the mouth of the opening down into the opening and is of less diameter than the opening, so that while it will assist to crowd down a charge into a pocket it will allow any excess to escape around the sides of the plunger back into the chamber 2. The length of stroke of the plunger is regulated 80 by varying the position of the wrist-pin 16 in slot 17 of the plunger-rod 18. Preferably 85

the plunger is made of fire-brick or other suitable infusible material. The reciprocation of the plunger is effected through the medium of the rod 19, having a roller 20 engaging a groove 21 on cam 22, carried by shaft 14, the design and arrangement of the parts being such that as the table is moving the plunger is retracted upward above the mouth of opening 7 to allow the latter to fill, the top of the table serving as a temporary closure. As soon as the table stops with a pocket between plates 8 and 7' and in line with opening 7 the plunger makes a rapid descent, forcing a quantity of glass into and filling the pocket, the excess in opening 7 displaced by the plunger escaping, as before stated, back into chamber 2. The plunger is preferably concaved on its bottom, and the pockets are provided with minute perforations 24 for the escape of air.

The size and number of the pockets may vary according to conditions, and it is obvious that various changes in details of construction of the apparatus may be made without departing from the principle of my invention.

Having thus described my invention, what I claim, and desire to secure by Letters Patent, is—

1. In a glass measuring and delivering apparatus, the combination with a melting-pot, a chamber leading therefrom, and means controlling communication between the pot and chamber, said chamber having a delivery-opening, of a carrier rotatably mounted beneath said chamber and provided with pockets adapted to be successively alined with said opening, receptacles fitted to the table in line with the pockets, and means for accelerating the delivery of the molten glass to the receptacles.

2. In glass-working apparatus, the combination with a source of liquid glass, of a rotatable carrier, open-ended receptacles adapted to contain a predetermined quantity of liquid glass said receptacles depending from the under side of the carrier and successively interposed in the course of liquid-supply, and a closure for the bottom of said receptacles, said closure yieldingly supported independent of the carrier.

3. In a glass measuring and delivering apparatus, the combination with a source of liquid-glass supply of a perforated rotary table, means for giving said table a step-by-step movement and open-ended measuring-receptacles removably secured to, and depending from, the under side of said table in line with the perforations therein and interposable in the path of the liquid, and a depressible bottom closure supported independent of the table for said receptacles.

4. In a glass measuring and delivering apparatus, the combination with a source of liquid-glass supply having a delivery-aperture,

of a rotary carrier, means for giving said carrier a step-by-step movement, open-ended measuring-receptacles depending from the under side of the carrier and alined with pockets therein, said receptacles adapted to be successively brought into the path of the liquid, and a bottom closure for and supported relative to the path of the receptacles and independent of the carrier.

5. In a glass measuring and delivery apparatus, the combination with a source of liquid-glass supply, of a rotatable carrier having radially-disposed pockets, open-ended measuring-receptacles removably fitted to and depending from the under side of the carrier in line with the pockets, means for rotating the carrier to bring the receptacles successively in line with the liquid-outlet, and a closure yieldingly supported in line with the liquid-outlet and adapted to serve as a bottom for successive receptacles.

6. In a glass measuring and delivery apparatus, the combination with a source of liquid-glass supply, of a rotatable carrier open-ended measuring-receptacles depending from the under side of the carrier and means whereby they are brought successively in the path of liquid-supply, and bottom closure means for said receptacles relative to the path thereof, said closure means including a yieldingly-supported plate.

7. In a glass measuring and delivering apparatus, the combination with a melting-pot and a chambered extension thereof adapted to contain molten glass and having a discharge-orifice, a rotatable carrier journaled beneath said extension, receptacles on said carrier registrable successively with said orifice, means within the chamber and operating through said discharge-orifice for aiding the feed to said receptacle, and means independent of said last-named feed-aiding means governing the discharge from the chamber.

8. In glass measuring and delivering apparatus, the combination with a melting-pot and a chambered extension thereof adapted to contain molten glass and having a discharge-orifice, a rotatable carrier, open-ended receptacles on said carrier registrable with said orifice, said carrier arranged to cooperate with the walls of said orifice as a slide-valve to control the flow of the liquid, and a part suitably supported relative to said orifice and arranged to cover and uncover the bottom of the receptacles in the rotation of the carrier.

9. In a glass measuring and delivering apparatus, the combination with a melting-pot and a glass-containing-chamber extension thereof having a discharge-orifice, of a table rotatable relative to said orifice, open-ended receptacles removably secured to the under side of said table and successively registrable with said orifice, a hollow perforated face-plate intermediate the chamber and table

- and registering with said orifice, connections between the interior of said face-plate and a source of cooling fluid-supply and a yieldingly-supported closure for the receptacles arranged relative to the path of movement of the latter and serving to cover the bottom of a receptacle during one step movement of the carrier and to uncover said receptacle during a succeeding step movement of said carrier.
10. In apparatus of the class described, the combination with a glass-containing chamber having a discharge-orifice and a rotatable table and means for imparting to the same a step-by-step movement, of an open-ended receptacle registerable with said orifice, a yieldingly-supported bottom closure for said receptacle located relative to said orifice said closure having a length approximately equal to the length of one step movement of the table, and means for causing said receptacle to traverse the space intermediate of the discharge end of said orifice and said closure.
15. In apparatus of the class described, the combination with a melting-pot, and a glass-containing chamber extending therefrom and having a discharge-orifice, of a rotatable carrier journalled beneath said extension, measuring-receptacles thereon registerable successively with said orifice, means for controlling the flow through the latter, and mechanical means for assisting in the filling of said receptacles.
20. In apparatus of the class described, the combination with a melting-pot, and a glass-

containing chamber extending therefrom and 35 having a discharge-orifice, of a rotatable carrier journalled beneath said extension, measuring-receptacles thereon registerable successively with said orifice, and mechanical means including a reciprocating plunger for 40 assisting in the filling of said receptacles.

13. In apparatus of the class described, the combination with a glass-containing chamber having a discharge-orifice, of a rotatable carrier, measuring-receptacles thereon registerable successively with said orifice, and co-operating with the mouth of said orifice to control the flow through the latter, and mechanical means including a reciprocating plunger for assisting in the filling of said receptacles, and means for giving said plunger and carrier a coördinate movement.

14. In apparatus of the class described, the combination with a glass-containing chamber having a discharge-orifice a rotatable carrier, measuring-receptacles thereon registerable successively with said orifice, a plunger reciprocal in said orifice and means for giving said plunger and carrier a coördinate movement.

In testimony whereof I have hereunto set my hand in presence of two subscribing witnesses..

WALTER D. MORRISON.
